CLAIM

What is claimed is an ornamental design for a smartphone packaging and virtual reality headset, as shown and described herein.

DESCRIPTION

FIG. 1 is a front perspective view of a smartphone packaging and virtual reality headset;
 FIG. 2 is a rear perspective view of the smartphone packaging and virtual reality headset shown in FIG. 1;
 FIG. 3 is a front view of the smartphone packaging and virtual reality headset shown in FIG. 1;

FIG. 4 is a rear view of the smartphone packaging and virtual reality headset shown in FIG. 1;
 FIG. 5 is a left-side view of the smartphone packaging and virtual reality headset shown in FIG. 1;
 FIG. 6 is a right-side view of the smartphone packaging and virtual reality headset shown in FIG. 1;
 FIG. 7 is a top-side view of the smartphone packaging and virtual reality headset shown in FIG. 1;
 FIG. 8 is a bottom-side view of the smartphone packaging and virtual reality headset shown in FIG. 1;
 FIG. 9 is an expanded, front perspective view of the smartphone packaging and virtual reality headset shown in FIG. 1;
 FIG. 10 is a front perspective view of a smartphone packaging and virtual reality headset;
 FIG. 11 is a rear perspective view of the smartphone packaging and virtual reality headset shown in FIG. 10;
 FIG. 12 is a front view of the smartphone packaging and virtual reality headset shown in FIG. 10;
 FIG. 13 is a rear view of the smartphone packaging and virtual reality headset shown in FIG. 10;
 FIG. 14 is a left-side view of the virtual reality headset shown in FIG. 10;
 FIG. 15 is a right-side view of the virtual reality headset shown in FIG. 10;
 FIG. 16 is a top-side view of the virtual reality headset shown in FIG. 10;
 FIG. 17 is a bottom-side view of the virtual reality headset shown in FIG. 10;
 FIG. 18 is an expanded, front perspective view of the smartphone packaging and virtual reality headset shown in FIG. 10;
 FIG. 19 is a front perspective view of a smartphone packaging and virtual reality headset;
 FIG. 20 is a rear perspective view of the smartphone packaging and virtual reality headset shown in FIG. 19;
 FIG. 21 is a front view of the smartphone packaging and virtual reality headset shown in FIG. 19;
 FIG. 22 is a rear view of the smartphone packaging and virtual reality headset shown in FIG. 19;
 FIG. 23 is a left-side view of the virtual reality headset shown in FIG. 19;
 FIG. 24 is a right-side view of the virtual reality headset shown in FIG. 19;
 FIG. 25 is a top-side view of the virtual reality headset shown in FIG. 19;
 FIG. 26 is a bottom-side view of the virtual reality headset shown in FIG. 19; and,
 FIG. 27 is an expanded, front perspective view of the smartphone packaging and virtual reality headset shown in FIG. 19.

Any broken lines in the drawing are for purposes of illustrating portions of the virtual reality headset and form no part of the claimed design.
